Primary Examiner — Charles Hanson(57) **CLAIM**

The ornamental design for a brake release handle, shown and described.

DESCRIPTION

FIG. 1 is a perspective view of the handle on a vehicle;
 FIG. 2 is a perspective view of the handle;
 FIG. 3 is a top plan view of the handle;
 FIG. 4 is a bottom view of the handle;
 FIG. 5 is a side elevational view of the handle;
 FIG. 6 is an end view of the pivoted end of the handle; and,
 FIG. 7 is an end view of the lever end of the handle.
 The broken line showing of the wheelchair is included for the purpose of illustrating environment and forms no part of the claimed design.

1 Claim, 3 Drawing Sheets# US D805,004 S
